SHUTTLE LATCHING MECHANISM

Raymond H. Book, Sterling, and Lee E. Gilbert,
Dixon, Ill., assignors to Reynolds Wire Co.,
Dixon, Ill., a corporation of Illinois

Application January 25, 1946, Serial No. 643,216

10 Claims. (Cl. 139—141)

1

This invention relates to shuttle latching mechanism for shuttles in looms in which the shuttles are positively transferred through the warp in a weaving process.

The invention is particularly designed for use in looms for weaving wire although it is equally applicable for weaving fabric cloth.

In the operation of a loom, two carrying arms reciprocate through the warp of the weave from the sides thereof and meet midway between the sides. The shuttle is carried on one carrying arm until the two carrying arms meet, and then it is transferred to the other carrying arm. The weft wire emerges from a bobbin carried in the shuttle.

At the point of juncture between the carrying arms, due to the speed of the arms and the momentum of the shuttle, there is usually a clash in transferring the shuttle from one arm to the other, resulting in loud noises, and serious wear and tear on the parts.

It is an object of the present invention to reduce the force of impact blow between the shuttle and carrying arms.

In our invention, the carrying arms have slowed down appreciably when the shuttle is about to be transferred, the residual impact force between the shuttle and empty carrying arm being utilized to operate the latching mechanism within the shuttle to latch the shuttle to that arm.

Another object of the invention is to construct a sturdy shuttle latching mechanism which will withstand wear and tear and yet be simple and economical in construction.

Still another object of the invention is to insure that the parts of the shuttle latching mechanism that latch onto the carrying arms are in positive engagement therewith and are constantly biased to latched position.

With these and other objects in view, our invention consists in the construction, arrangement and combination of the various parts of our device whereby the objects contemplated are attained, as hereinafter more fully set forth, pointed out in the claims and illustrated in the accompanying drawings, wherein:

Fig. 1 is a plan view of the shuttle showing the two carrying arms inserted therein.

Fig. 2 is a view showing the shuttle after it has been carried to the extreme right.

2

Fig. 3 shows the shuttle after it has been returned to the center and is about to be connected to the carrying arm to the left.

Fig. 4 shows the shuttle an instant after Fig. 3, that is, just after the shuttle has been connected to the carrying arm to the left and before it is actually drawn to the left.

Fig. 5 shows the shuttle at its limit of movement to the left.

10 Fig. 6 is a side view of the shuttle body, and Fig. 7 is an end view of the shuttle body.

Referring now in detail to the drawings, the shuttle body is shown at 8. Detachably mounted in the shuttle body is a bobbin indicated generally at 9 from which weft wire is supplied for the weaving process. This bobbin does not form a part of the present invention but is indicated to complete the description of the operation of the shuttle.

20 Two carrying arms are shown at 10 and 11. The operation of the carrying arms may be accomplished by any of the well known means for reciprocating the arms toward and away from each other. The carrying arm 10 enters channel

25 10' and the carrying arm 11 enters the channel 11' of the shuttle body. In the center of the shuttle body is a cut-out portion or cavity 12 in which are positioned two arms 14 and 15 pivoted on pins 16 and 17, respectively, inserted through the

30 arms and the shuttle body. It will be noted that the arms 14 and 15 are oppositely directed and are pivoted near each other at the center of the shuttle body. At the free ends of the arms 14 and 15 are projections or hooks 19 and 20, respectively,

35 adapted to engage in notches 21 and 22 in the carrying arms 10 and 11, respectively. Cam means 24 and 25 are formed on the pivoted arms 14 and 15 between the pivots and free ends thereof. A leaf spring 26 is positioned in the

40 cavity 12 with its ends engaging projections 27 and 29 on the free ends of the pivot arms 14 and 15. An inwardly projected point 30 on the shuttle body extends into the cavity 12 and serves as a point of reaction against the spring 26 thereby

45 biasing the spring against the pivoted arms 14 and 15 and urging them into contact with the carrying arms 10 and 11. The hooks 19 and 20, and the notches 21 and 22 in the carrying arms 10 and 11, are cut at such an angle that they tend 50 to remain in engagement when the carrying arms

draw the shuttle away from the center of the machine.

Numeral 31 indicates a slidable member or block which is positioned in the cavity 12 in line with channels 10' and 11' substantially midway longitudinally of the shuttle body. The upper corners of the slidable member 31 are beveled as indicated at 32 for engaging cam means 24 and 25 on the pivoted arms 14 and 15, the purpose of which will be described later.

A rockable member 34 is pivotally secured to slidable member 31 by means of a pin 35 extending through the two members and into a horizontal, elongated slot 36 formed in the shuttle body. These two members are movable bodily longitudinally as limited by the slot 36, and in addition the rockable member 34 is rockable about pivot 35 with respect to the slidable member 31 to a limited extent. The member 34 has a peculiar formation, being generally of a double wedge shape so that the outer ends 37 and 39 thereof can alternately come into contact with the inner ends of the carrying arms 10 and 11, respectively, when the member has been rocked in one or the other direction about pivot 35. A pin or projection 40 is mounted on the rockable member 34, the purpose of which will be described later.

Operation

Fig. 1 shows the device as it is about to be drawn to the right by carrying arm 11, and the pivoted arm 14 is out of engagement with its carrying arm 10; the shuttle is therefore free to be carried to the right.

Figure 2 shows the shuttle at the limit of movement to the right. At this point a stud 41 mounted on the loom frame where pin 40 comes into contact with it, rocks the rockable member 34 clockwise, bringing the end 39 thereof out of alignment with the carrying arm 11 and bringing the end 37 up into the channel 10' where it will be in line with the carrying arm 10. The shuttle is now about to return to the left.

Figure 3 shows the shuttle after it has been returned from the right to the center of the machine. This figure shows the inner end of the carrying arm 10 in contact with the end 37 of the rockable member 34. Continued movement of the shuttle to the left against the carrying arm 10 will force the rockable member 34 and slidable member 31 to the right to the limit of the slot 36. The position of the various parts of the latching mechanism after this movement occurs is shown in Fig. 4. At this point there is no further relative movement between the shuttle and the carrying arm 10. As a result of the movement of the slidable member 31 to the right, it moves out of contact with cam means 24 and pivoted arm 14 then becomes latched to the carrying arm 10. In the same movement, the slidable member 31 bears on cam means 25 forcing the pivoted arm 15 out of engagement with the carrying arm 11, thereby releasing the shuttle from the carrying arm 11. The shuttle is now free to be carried to the left on the carrying arm 10.

Fig. 5 shows the shuttle as it is carried to the limit of its movement to the left where a stud or projection 42 is mounted on the loom frame. At this point, pin 40 on the rockable member 34 comes in contact with this stud, swinging the rockable member 34 counter-clockwise to the position shown in Figure 5 where the end 37 is brought out of alignment with the carrying arm 10 and the end 39 is brought into channel 11' and into alignment with the carrying arm 11. The

shuttle is now returned to the right to the center of the loom, where the procedure is repeated.

It will be noted that the rockable member 34 serves as an extension of the length of the slidable member 31 alternately in the direction desired. This rockable member serves as a means for moving the slidable member 31 while maintaining an effective spacing between the slidable member and the carrying arms, and also prevents the carrying arms from contacting the cam means 24 and 25.

When the carrying arms 10 and 11 meet there is a tendency for the shuttle to be pushed farther onto the arm on which it already rests, shortening the length of travel of the slidable member 31 which would hinder the latching and unlatching action. To prevent this, hardened steel stops 43 are secured to the carrying arms 10 and 11 at such a distance from their inner ends as to permit entrance into the channels 10' and 11' the proper extent.

Figures 6 and 7 show the general shape of the shuttle body and indicate the positions of the channels 10' and 11'.

From the foregoing it will be seen that when the shuttle has reached the center of the loom as for example, at the point shown in Figure 3, there is very little further movement of the shuttle; the only additional movement that will take place is that indicated by Figures 3 and 4, that is, just sufficient to operate the latching mechanism. This construction therefore substantially reduces shock and although the shuttle is subjected to hard service, this construction is simple and rugged enough to withstand wear for a great length of time.

While we have shown a specific embodiment of our invention, we do not expect it to be limiting but only illustrative, and numerous modifications in detail are intended to be within the spirit and scope of the appended claims.

We claim:

1. A shuttle and latching mechanism therefor for use in a loom of the type having a pair of reciprocating carrying arms adapted alternately to carry a shuttle, said shuttle latching mechanism comprising, in combination, connecting means for alternately connecting the shuttle to said carrying arms, a slidable member for disconnecting said connecting means from said carrying arms, said slidable member being operable by the thrust of said carrying arms, and a rockable member mounted on and carried by said slidable member for receiving the thrust from said carrying arms and transmitting the same to said slidable member.

2. A shuttle and latching mechanism therefor for use in a loom of the type having a pair of reciprocating arms adapted to alternately carry a shuttle, said shuttle latching mechanism comprising, in combination, a pivoted arm cooperating with each of said carrying arms for alternately connecting the shuttle to its respective carrying arm, spring means biasing said pivoted arms into engagement with their respective carrying arms, cam means on each of said pivoted arms, and a slidable member adapted to engage either of said cam means and thereby unlatch its corresponding pivoted arm from its respective carrying arm, said slidable member being operable by the thrust of said carrying arms.

3. A shuttle and latching mechanism therefor for use in a loom of the type having a pair of reciprocating carrying arms adapted to alter-

nately carry a shuttle, said shuttle latching mechanism comprising in combination, a latching member cooperating with each of said carrying arms for alternately connecting the shuttle to its respective carrying arm, means tending to latch said latching members to their respective carrying arms, a slidale member adapted to unlatch said latching members from their respective carrying arms, said slidale member being operable by the thrust of said carrying arms, and means mounted on said slidale member for increasing its effective length in either direction alternately.

4. A shuttle latching mechanism for use in a loom of the type having a pair of reciprocating carrying arms which move toward and away from one another and are adapted to alternately carry a shuttle, said shuttle latching mechanism comprising, in combination, a shuttle, a latching member cooperating with each of said carrying arms for alternately connecting the shuttle to its respective carrying arm, means tending to latch said latching members to their respective carrying arms, a slidale member adapted to unlatch said latching members from their respective carrying arms, said slidale member being operable by the thrust of said carrying arms, and a rockable member mounted on and movable with said slidale member for receiving the thrust from said carrying arms and transmitting the same to said slidale member, and said rockable member increasing the effective length of said slidale member alternately in the direction thereof toward the empty carrying arm.

5. Shuttle latching mechanism for use in a loom of the type having a pair of reciprocating carrying arms which move toward and away from one another, and are adapted alternately to carry a shuttle, said shuttle latching mechanism comprising, in combination, a latching member cooperating with each of said carrying arms for alternately connecting the shuttle to its respective carrying arm, means tending to force said latching members into latching position, a slidale member for unlatching said latching members, said slidale member being operated by the inward stroke of the respective carrying arms, and a rockable member carried by and movable with said slidale member for receiving thrust from said carrying arms and transmitting the same to said slidale member, said rockable member being positionable responsive to the outward stroke of said carrying arms.

6. Shuttle latching mechanism for use in a loom of the type having projections thereon and a pair of reciprocating carrying arms which move toward and away from one another and are adapted alternately to carry a shuttle, said shuttle latching mechanism comprising in combination, a latching member cooperating with each of said carrying arms for alternately connecting the shuttle to its respective carrying arm, means tending to force said latching members into latching position, a slidale member for unlatching said latching members, said slidale member being operated by the thrust of said carrying arms, and a rockable member carried by and movable with said slidale member for receiving the thrust from said carrying arms and transmitting the same to said slidale member, said rockable member being positionable by contact with projections on the loom while being carried by said carrying arms.

7. Shuttle latching mechanism for use in a loom of the type having projections thereon and a pair of reciprocating carrying arms which move toward and away from one another and are adapted alternately to carry a shuttle, said shuttle latching mechanism comprising in combination, a latching member cooperating with each of said carrying arms for alternately connecting the shuttle to its respective carrying arm, means tending to force said latching members into latched position, a slidale member for unlatching said latching members, said slidale member being operated by the thrust of said carrying arms, and a rockable member carried by and movable with said slidale member for receiving the thrust from said carrying arms and transmitting the same to said slidale member, said rockable member being positionable by contact with said projections on the loom at the end of the outward stroke of said respective carrying arms.

8. A shuttle latching mechanism for use in a loom of the type having a pair of reciprocating carrying arms adapted to alternately carry a shuttle, said shuttle latch mechanism comprising, in combination, a pair of oppositely directed pivoted arms adapted to engage and latch to their respective carrying arms for connecting the shuttle thereto, said pivoted arms having their pivots adjacent each other and having projections on the free ends thereof for engaging cooperating detents on said carrying arms, cam means on each of said pivoted arms positioned between the pivots and free ends thereof, a leaf spring biasing said pivoted arms into engagement with said carrying arms, and a slidale member adjacent the pivots of said pivoted arms coacting with said cam means for moving said pivoted arms to unlatched position, said slidale member being operable by the thrust of said carrying arms.

9. A shuttle latching mechanism for use in a loom of the type having a pair of reciprocating carrying arms adapted to alternately carry a shuttle, said shuttle latch mechanism comprising, in combination, a pair of oppositely directed pivoted arms adapted to engage and latch to their respective carrying arms for connecting the shuttle thereto, said pivoted arms having their pivots adjacent each other and having projections on the free ends thereof for engaging cooperating detents on said carrying arms, cam means on each of said pivoted arms positioned between the pivots and free ends thereof, a leaf spring biasing said pivoted arms into engagement with said carrying arms, a slidale member adjacent the pivots of said pivoted arms coacting with said cam means for moving said pivoted arms to unlatched position, said slidale member being operable by the thrust of said carrying arms, and a rockable member mounted on and movable with said slidale member, said rockable member being positionable to extend beyond the ends of said slidale member alternately for receiving the thrust from said carrying arms and transmitting the same to said slidale member.

10. A shuttle latching mechanism for use in a loom of the type having a pair of reciprocating carrying arms adapted to alternately carry a shuttle, said shuttle latching mechanism comprising, in combination, a pair of oppositely directed pivoted arms adapted to engage and latch to their respective carrying arms for connecting the shuttle thereto, said pivoted arms having their pivots adjacent each other and having projections on the free ends thereof for engaging cooperating detents on said carrying arms, cam means on each

of said pivoted arms positioned between the pivots and free ends thereof, a leaf spring biasing said pivoted arms into engagement with said carrying arms, and a slideable member adjacent the pivots of said pivoted arms coacting with said cam means for moving said pivoted arms to unlatched position, said slideable member being operable by the thrust of said carrying arms, and being of such length as to coact with only one of said cam means at a time, whereby, at all times one of said pivoted arms is biased into engagement with its respective carrying arm.
